FOOD PACKAGING TRAY OR SIMILAR ARTICLE

Alex G. Dunton, Jr., Richmond, Va., assignor to Reynolds Metals Company, Richmond, Va.

Filed Feb. 16, 1970, Ser. No. 21,440

Term of patent 14 years

Int. Cl. D9—04

U.S. Cl. D9—187

FIG-1

FIG-2

FIG-3

FIG-4

FIG. 1 is a top perspective view of a food packaging tray or similar article embodying my new design;

FIG. 2 is a bottom plan view thereof on an enlarged scale;

FIG. 3 is a cross-sectional view taken on the line 3—3 of FIG. 2; and

FIG. 4 is a cross-sectional view taken on the line 4—4 of FIG. 2.

I claim:

The ornamental design for a food packaging tray or similar article, as shown.
